Christopher Pilling(57) **CLAIM**

The ornamental design for a cylindrical s'more, as shown and described.

DESCRIPTION

FIG. 1 is a front perspective view of the cylindrical s'more; FIG. 2 is a front elevation view of the cylindrical s'more, the rear elevation view being a mirror image thereof;

FIG. 3 is a right side elevation view of the cylindrical s'more, the left side elevation view being a mirror image thereof;

FIG. 4 is a top plan view of the cylindrical s'more; and, FIG. 5 is a bottom plan view of the cylindrical s'more. The stippled shading and the line shading shown in FIGS.

1-5 represent a contrasting appearance.
